TRANSFER STAMPING MACHINE

Frank C. Kingsland, Gates Mills, and Sidney A.
Kingsland, Willoughby, Ohio

Application December 21, 1949, Serial No. 134,166

9 Claims. (Cl. 41—1)

1

Our invention relates to a machine, semi-automatic or automatic in its operation, particularly for the application of dry transfers to linen, fabrics, textiles, and cloth fabrics of any and every kind for marking same.

One of the principal objects of the invention is to provide a machine for the purpose of stamping names, marks, or character on linens, fabric, etc., for a dry transfer, by means of a heating element, with a built-in thermostat which maintains, at all times, when in operation, the proper temperature, or heat, in such element, required for making the transfer to the desired cloth or fabric.

Another object of this invention is to provide a machine of the type described herein that will provide the proper amount of pressure on the transfer at any position of the down stroke of the piston.

Another object of this invention is to provide a machine of the type previously described herein, having a switch, operated practically without any fatigue on the part of the operator, which switch is operated by a slight touch of the foot of the operator, and which switch controls the operation of the piston, to which the heating element is attached, for the marking operation.

Another object of the invention is to provide a machine of a type previously described herein, which has a pressurestat to regulate the proper length of time the heating element is to be kept in contact with the transfer to properly mark the cloth, or fabric, and at the same time maintains the correct pressure exerted on the heating element by the piston at any point on the downward stroke of the piston.

Another object of this invention is to provide a machine of the type previously described herein which operates entirely by air pressure supplied by a unit built within the body part of the machine, or may be adapted, without such unit, to receive necessary air pressure by connecting to a service line, the machine being thus operated by clean air, in place of a fluid of any kind, eliminating all possibility of soiling any material being stamped.

Another object of this invention is to provide a machine of the type previously described herein with a detachable heating element so that any desired design, or shape, of such element may be used, and a manifold for automatically removing the used transfer paper and moving it towards a receptacle at the rear of machine.

Another object of the invention is to provide a machine of the type previously described here-

2

in with a safety switch for instantly stopping the downward stroke of the heating element at any point and instantly forcing such element and shaft back to their original positions, which machine may have an automatic counter to register the number of pieces of lines, fabric, etc., marked.

Another object of our invention is to provide a machine that can be converted to automatic operation for the application of a transfer to the cloth, or fabric, to be stamped, the only manual operation required being the feeding of the cloth or fabric, to be stamped and the placing of the transfer on such cloth, or fabric.

Another object of this invention is to provide a machine of the type and design described previously herein mounted on rollers, or casters, so as to permit it to be moved easily from one place to another, particularly to move it to where a stock of cloth, or fabrics, are located instead of having to move all such stock to where the machine is located.

Another object of the invention is to provide a machine of the type and design shown with means for changing such machine from a "foot control" to "automatic" operation.

Another object of the invention is to provide a machine of the type described which has a combined automatic interference and safety switch built in the body of the heating element which will permit the machine to operate only when the temperature of the heating element is proper, as predetermined, for correctly applying transfers.

Many other objects attainable by the use of this invention will become apparent by a reading of the description and a study of the accompanying drawings, in which:

Fig. 1 is a side elevation view of the invention, or machine, partly sectional, taken on line 1—1 of Fig. 5.

Fig. 2 is a longitudinal sectional view of the cylinder and piston therein;

Fig. 3 is a sectional view of the five-way valve unit of the invention;

Fig. 4 is an enlarged fragmentary view of the automatic switch control of the machine;

Fig. 5 is a front elevation view, partly sectional, of the machine; and

Fig. 6 is a schematic working circuit diagram. Referring more in detail to the drawings:

1 refers to the complete machine, which is supported on four legs L equipped with rollers for easily moving the machine about. 2 refers to a back panel, or instrument board (preferably made of cast metal). 3 is a main supporting frame of

the machine and is desirably cast in metal for greater strength and rigidity.

4 is a complete cylinder for control of the transfer applying means and has a piston and chamber comprising, as per Fig. 2, a head 5 and a base 6, a piston rod, or shaft 7, and piston 27 having suitable gaskets or seals 31 on each surface thereof, and gasket 29 and wiping gasket 28 in the base 6. Cylinder 4 is suitably secured to the frame 3. 32 is an air port and 30 is the interior space or bore of the cylinder 4. 25 is an air inlet fitting connected to port 32 and 24 an air port for the cylinder 4. An air supply tube 9 connects through fitting 26 with a tube 8 that connects to and telescopically receives an extension tube 8A with an air-tight seal therebetween. The tube 8A moves with the piston assembly and connects to a manifold, or "blower" tube 18 attached to an iron 15, which acts to "blow" a used transfer off the material immediately after the stamping or transfer action is complete, as brought out in detail hereinafter. Air supply and exhaust tube 10 connects with inlet 25 to provide air for operating the piston 27. 11 is an inlet and exhaust air tube connected to outlet 24. 12 refers to supports for securing the tube 8 to the cylinder 4.

14 are heat vanes, or deflectors suitably secured to the iron 15. 16 is a hand operated switch lever pivotally carried by the iron 15 for changing the cycle of operation of the machine to "foot" control, or to "automatic," as may be desired. 17 is a conventional fitting or member for attaching the iron 15 to the shaft 7 for movement therewith and permits the iron to be easily removed from and secured to such shaft. 19 is a safety switch bracket that extends across the front of the iron and is pivotally secured thereto at its ends and which protrudes from the iron to contact the hand or hands of the operator, to instantly stop the descent of the iron 15 in case the operator's hands are in such a position as to be in danger of being caught under the descending iron. Moving the bracket 19 upwardly returns the iron to its up position, as described hereinafter. 13 is the base part of the iron 15 that contacts a transfer to effect a transfer action thereon. 20 is a plate connecting the cooling vanes 14 to the heated base 13 of the iron by means of heat conductors 21A. 22 are electrical cords for providing current to form heat energy for the iron unit. 23 is a pad on the top surface of a wood base 1A of the machine upon which the material to be stamped is placed and is immediately underneath the iron 15 which is movable vertically by the piston rod 7. 33 is an electric wire cable case for leads 126 and 127 that connect to a control switch 34 which has a contact point 34A extending down therefrom. 16A is a contact point on the automatic lever 16, located on the top thereof. By moving such lever to one position at a right angle to the iron 15, the contact point 16A will strike contact point 34A to close a circuit when the heating element, or iron, reaches its up position, so that it will automatically repeat its cycle, as described. By changing such automatic lever to its other position, parallel with the length of the iron, the machine will then repeat its cycle only by means of the foot pedal control by operator, as described hereinafter.

35 is a "penetration" regulator rheostat for "light" or "heavy" material to be stamped, and 36 is a speed control rheostat for the cycle of the machine to make it fast, or slow. 37 is a

light, usually green, to indicate when lit that the machine is ready for operation and the iron is at working temperature. 39 is a pressure indicating dial that connects to an air supply line. 40 is a counter to tally the number of pieces marked by the machine. 41 is a starting switch for the machine.

The device A, Fig. 3, represents a five way air valve for controlling the operation of the machine and the components thereof.

The wood base, or table, 1A, may have wood sides 100 to enclose same partially. The panel 2 has an opening 18 provided therein to permit the used transfers to be blown off the table 1A by the blower means previously described.

The different items shown in the schematic circuit diagram (Fig. 6) are all standard equipment and are used as auxiliary to, and in conjunction with, the device of this invention.

Circuit diagram

In the foregoing specification, it should be noted that the five-way valve referred to is a valve which has two positions and that the valve is positioned in one extremity or the other of its movement by certain solenoid control means provided therefor.

Reference now should be had to the schematic circuit diagram shown in Fig. 6 of the drawings. In this figure it is seen that two power supply lines 100 and 101 are provided which supply electrical energy for operation of the entire apparatus of the invention. The lead 100 connects through a lead 102 to a thermostat 103 that controls a switch 104 with the other side of the switch 104 being connected to a resistance heater unit 105 that is located in the iron 15 used in the device of the invention. The other side of the heating element 105 connects back to the power supply lead 101 so that when the main control switch 41 is closed, electrical energy will be supplied to the heat element 105 as long as the thermostat 103 is closed. The signal light 37 is provided in parallel relation to the thermostat 103 by wires 107 and 108 so that when the thermostat is open, the circuit there around is through the light 106 and causes such light to be lit and indicate that the thermostat is open whereas when the thermostat is closed, it effects a short circuit around the light 106 and prevents operation of the light. This thermostat 103 is associated with the heater resistant unit 105 so that the thermostat is opened by such heater resistor when at a predetermined temperature, such as about 400° F., so that heat energy will be supplied to the resistor 105 until it reaches a predetermined temperature. When the thermostat 103 is open, the light 106 absorbs so much energy that only a very low current flows through the register 105 and does not effectively heat same.

In starting up the apparatus of the invention, it is greatly desirable that the heater unit be retained in its up position until the device is ready for operation. Thus a so-called blocking thermostat 109 is provided for controlling a switch 110. This switch 110 is connected by a lead 111 to one terminal of a solenoid coil or solenoid 112. The other terminal of the solenoid 112 is connected by a lead 113 to the power supply lead 101. Lead 114 connects the power supply lead 102 to the other terminal of the thermostat 109 so that when the blocking thermostat 109 is closed the solenoid 112 is continuously energized and retains the five-way valve device in a fixed

position to set up pressure in the cylinder 4 to retain the piston rod thereof in its up position.

When the heating resistance 105 of the iron 115 reaches its predetermined temperature, the thermostat 109 opens switch 110 and further action of the two position valve of the invention may be controlled by means of either the normally open foot control switch or the automatic switch of the apparatus of the invention. For the so-called semi-automatic operation of the invention by use of the foot switch referred to hereinbefore, a foot controlled switch 115 is connected to the power supply lead 100 and connects to a lead 116 that connects in turn to one terminal of a second solenoid 117 that is associated with the two position valve for controlling the setting or operation thereof. The other terminal of the solenoid 117 connects through a lead 118 to the remaining power supply lead 101 so that closing the switch 115 instantaneously causes the solenoid 117 to be energized and moves the valve to its down position. Such position of the valve provides air pressure supply to the tube 10 for forcing the piston rod downwardly of the cylinder in which it is slidably received and causes the iron head to move down into desired relationship with the goods on which a transfer is to be applied. Such pressure being transmitted to the conduit or tube 10 also is carried to a conduit 120 which connects to a pressurestat 121 the pressure in and setting of which controls a switch 122. Thus when a predetermined pressure is set up in the line 10 and through it to the line 120, the pressurestat 121 will close switch 122. Such action occurs only when the pressure in the line 10 has forced the piston rod therein to move downwardly of the cylinder 4 to the bottom thereof. By controlling the setting of a valve 123 that is provided in the line 120 and has a variable escape, or relief orifice provided wherein, the rate of build-up of pressure in the pressurestat 121 can be controlled to a desired value. Control rheostat 35 controls the size of the orifice in the valve 123. Thus after the piston rod 7 has moved to its lower extremity, a certain predetermined time will elapse before the pressurestat 121 is actuated to close switch 122. Closure of the switch 122, which connects at one side to the power supply lead by a lead 124, closes a circuit through the effects actuation of the solenoid 112 by means of a connector lead 125. This actuation of the solenoid 112 will cause the control plunger for the five-way two position valve to be changed so that pressure will be supplied to the line or conduit 11 and effect a lifting movement of the heater iron and associated elements. It has already been noted that the solenoid 112 is connected to the power supply lead 101 by a connector lead 113.

In case it is desired to have automatic operation of the apparatus of the invention, the switch element 16 previously referred to herein is shown on the drawing in parallel relation to the foot control switch 115 so that when such switch is closed, as by properly positioning same plus movement of the heater iron and its associated means to its up position, the apparatus of the invention can be made to repeat its operative cycle, as desired by the operator of the machine. Leads 126 and 127 connect the automatic switch 16 in shunt or parallel relation to the foot control switch 115.

Usually it is necessary to have a slight time lag between the raising of the heater iron member and the next downward stroke thereof, even on

automatic operation of the machine, so that it is desirable to have a second pressurestat control provided in the apparatus of the invention and connected in the line 11. This pressurestat is indicated by the numeral 128 and in turn controls a switch 129 that is provided in the lead 127 so that a circuit only is closed through the automatic switch after a predetermined pressure has been built up in the lower portion of the cylinder 4. Rheostat 36 may control a vent orifice associated with the pressurestat 128 to regulate the time delay of the apparatus intermediate its operational cycles, similar to the connection and action of the valve 123.

As yet another feature of the apparatus of the invention, the safety control bracket 19 is connected to the switch 110 to close same and effect an immediate energization of the solenoid 112 when the operator's body or person strikes this control bracket 19 on its downward movement. Thus an immediate lifting action is exerted upon the piston rod 7 and associated means. The tube 9 connects to the five-way valve A to receive the exhaust from such valve when the piston is being raised through action of the solenoid 112.

Air pressure is supplied to the system by a conventional air compressor pump 140 that is driven by a motor 141. Motor 141 connects to lead 124 and by lead 142 to power supply lead 101. Output of pump 140 flows through tube 143 to the valve A. A counter device 40 is connected by lead 145 to lead 116 and by lead 146 to lead 101 to indicate the number of operations of the machine.

It has been established that it takes the correct amount of pressure, correct temperature, and the correct length of time for a heating element to remain in contact with a transfer to make the desired transfer and mark the cloth or fabric to be marked. Such length of time is regulated by the time indicator rheostat 35, which has a dial with two different markings, namely, light and heavy, to control the length of time that the iron 15 remains in contact with the "dry transfer" and cloth or fabric to be stamped. A pressure dial 39 is connected directly to the air supply line 143 for the five-way air valve A. By turning the knob 35 to heavy, the iron 15 is allowed to remain in contact with the "dry transfer" somewhat longer than at light in order to properly mark such cloth.

The safety switch bar 19 has a spring 19A that is secured to and moves with the iron, and draws the bar 19 to a normal non-operative position. Either by a slight upward pressure or touch by the operator, or by contacting the hand of the operator when it acts as an emergency to prevent injury to such operator, the switch bar closes the switch 110 to immediately stop the downward stroke of the iron and returns it to its up position.

The operation of the iron or heating elements is further controlled by means of the combination automatic interference and safety switch 110 located within the body of the heating element and which acts to automatically cause the machine to cease operating if for any cause the heating element has dropped to the point where it is impractical to correctly apply transfers. This switch will also prevent the operation of the machine in case the operator attempts to use the machine before waiting the period of time for the heating element to acquire its proper temperature.

It will be realized that friction is the only force

normally preventing movement of the piston 7. Conduit 200 of valve A is an exhaust line therefor. The control arm 16 is suitably pivotally secured to the movable head or iron assembly of the device of the invention.

This application is a continuation-in-part of our application Serial No. 16,108, filed March 20, 1948, now abandoned.

Having thus described our invention, what we claim is:

1. In a stamping machine a head member, a fluid cylinder having a piston member slidably received therein and extending therefrom, said head member being secured to the said piston member, a control valve for said cylinder as a means for regulating the pressure within said cylinder, an electric control means for changing the position of said control valve, and a means in the form of a switch for actuating the said control means.

2. In a stamping machine, a head member carrying an electric heater, an air operated cylinder having a piston member slidably received therein and extending therefrom, a head member secured to and operated by said piston member, a control valve for said cylinder as a means to regulate the pressure in said cylinder, an electric control means for changing the position of the said control valve, and a switch means for temporarily actuating said electric control means.

3. In a stamping machine, a head member carrying an electric heater, an air cylinder having a piston member slidably received therein and extending therefrom, said head member being secured to said piston member and operated by said piston member, a control valve for said cylinder as a means to regulate the pressure therein, said control valve having a slideable member therein and an electric control means for changing the position of the slideable member therein, a switch means carried by said head member as a means for actuating said electric control means, a pressure operable means connected to said cylinder, and a switch controlled by the said last named means to actuate said electric control means.

4. In a transfer applying machine, a head element having a switch associated therewith, a reciprocable means secured to said head element as a means for positioning same, a pair of solenoids as a means for controlling the position of the said reciprocable means, said solenoids having a power supplying means connected thereto and a safety bar pivotally carried by said element and connected to said switch to close same on the deflection of said safety bar, said switch being connected to one of said solenoid means in the power supply means therefor to energize said switch and move the said reciprocable means to a non-operative position upon deflection of said safety bar.

5. In a transfer applying machine, a head element carrying a heater element and a thermostat controlled by the temperature of the said heater element, a switch controlled by the said thermostat and being normally closed until a predetermined temperature is reached, a reciprocable means secured to said heater element and positioning same, a solenoid for holding the said reciprocable means in a non-operating position, a power supply means connected to said heater element and a master switch in the said power supply means for turning the machine on and off,

the first said switch being connected to said solenoid and power supply means to energize a part of said solenoid means to retain said reciprocable means in a given position until such time as said heater element reaches a predetermined temperature.

6. In a machine of the general class described, a cylinder means, a piston slidably positioned in said cylinder means, a head member secured to said piston and positioned thereby, air pressure supply means, valve means connecting said air pressure supply means to said cylinder means to control the air supply thereto and the position of said piston, electric means for controlling said valve means, a pressurestat connected to said cylinder means, and a switch in the power supply circuit of said electric means and controlled by said pressurestat to be closed on a predetermined pressure being set up in said cylinder.

7. In a machine of the general class described, a head carrying an electric heater element, a cylinder having a piston disposed therein and extending therefrom, the said piston as a means for positioning the said head, an air pressure distributor valve having a reciprocable control therein and an air pressure supply means connected to said valve, conduits connecting said valve to said cylinder as a means for supplying air thereto to move said piston dependent upon the position of said valve, a pair of solenoids positioned adjacent opposite ends of said control valve and each adapted to move such control to different operating positions on the actuation thereof, an energizing circuit for one of said solenoids for moving said head to an operating position, a switch in said circuit for temporarily closing same and affecting the operating movement of said head, a pressurestat connected to said cylinder for receiving the pressure therein when said piston is operatively positioned, a switch controlled by said pressurestat, and an electric power supply circuit connecting said last named circuit to said second solenoid for actuating same and moving said control of said valve whereby said piston and said head are moved to a non-operating position.

8. In a machine of the general class as described in claim 7, a second pressurestat connected to a second portion of said cylinder and controlling said first switch as a means to actuate said valve and move said head to an operative position.

9. In a machine of the general class as described in claim 8, an air exhaust tube connecting said cylinder to said head member to provide an air blast to the head member at a desired time, and an interference switch controlled by the temperature of the said heater element and connected to said means for preventing operation of said head member until said heater element is at a predetermined temperature.
